UNITED STATES PATENT OFFICE

GEORGE F. YAGER, OF TOLEDO, OHIO, ASSIGNOR TO THE BUNTING BRASS & BRONZE COMPANY, OF TOLEDO, OHIO, A CORPORATION OF OHIO

METAL WORKING MACHINE

Application filed July 14, 1930. Serial No. 467,907.

This invention relates generally to metal working machines such as drilling and broaching machines, and consists of certain novel features of construction, combinations 5 and arrangements of parts that will be hereinafter more fully described and particularly pointed out in the appended claims.

In the accompanying drawings:

Figure 1 is a fragmentary side elevation 10 of a machine embodying my invention;

Figure 2 is a fragmentary end elevation thereof;

Figure 3 is an elevation of the cam shaft and cams;

15 Figure 4 is a top plan view of a slightly modified construction;

Figure 5 is a fragmentary side elevation of the construction illustrated in Figure 4;

20 Figure 6 is a fragmentary end elevation 20 of the construction illustrated in Figures 4 and 5;

Figure 7 is a fragmentary vertical sectional view through the machine.

Referring now to the drawings, 1 is the 25 base or frame of the machine; 2 and 3 respectively are spindle heads slidably mounted upon the top 6 of the frame; and

7 are inverted L strips secured by bolts 8 to raised portions 9 of the frame 6 and serving 30 the dual function of guides and clamps for the heads 2 and 3 respectively. Thus when the bolts 8 are loosened the heads 2 and 3 may be adjusted in the guides 7 relative to each other, and when the bolts 8 are tightened 35 the heads 2 and 3 will be effectively held by the strips 7 in adjusted position.

10 and 11 respectively are rotating spindles journaled in bearings in the heads 2 and 3 respectively; 12 and 13 respectively 40 are pulleys rigid with the respective spindles 10 and 11 and adapted to be driven from a suitable source (not shown) by belts 14 and 15 respectively; 16 and 17 respectively are caps threaded upon the spindles 10 and 11 respectively at the inner ends thereof and provided at their inner ends with conical faces 18 and 19 respectively; and 20 and 21 respectively are collets slidably mounted in the spindles 10 and 11 and provided at 45 their inner ends with conical faces 22 and

23 respectively engageable with the conical faces 18 and 19 of the caps 16 and 17. As shown, the collets 20 and 21 have longitudinally extending slots 24 and 25 respectively and work engaging gripping surfaces 26 and 27 respectively. 28 and 29 respectively are hardened sleeves slidable within the spindles 10 and 11 respectively and having portions 30 and 31 respectively overlapping and slidably engaging the bases 32 and 33 respectively of L-shaped rabbets in the collets 20 and 21; and 34 and 35 respectively are tubular rams slidably mounted within the spindles 10 and 11 respectively and having portions 36 and 37 respectively overlapping and slidably engaging the bases 38 and 39 respectively of L-shaped rabbets in the hardened sleeves 28 and 29. Preferably the portions 30 and 31 respectively of the sleeves 28 and 29 and the portions 36 and 37 respectively of the rams 34 and 35 have conical faces 40, 41, 42 and 43 respectively. 44 and 45 respectively are coil springs sleeved about reduced portions 46 and 47 of the rams 34 and 35 and abutting shoulders 48 and 49 respectively thereof; 50 and 51 respectively are spring followers slidably mounted upon the reduced portions 46 and 47 and abutting the outer ends of the springs 44 and 45; 50' and 51' respectively are adjusting nuts for the springs 44 and 45; 52 and 53 respectively are dog holders upon the spindles 10 and 11 respectively at the outer ends thereof and having slots 54 and 55 respectively therein; 56 are dogs pivoted in the slots 54 and 55 respectively of the tubular dog holders 52 and 53 and having heel portions 57 engaging the spring followers 50 and 51; 58, 59 and 60 respectively are adjusting nuts for the dog holders 52 and 53 respectively; 62 and 63 respectively are dog engaging collars upon the tubular dog holders 52 and 53 respectively and having peripheral grooves or channels 64 and 65 respectively therein; 66 and 67 respectively are levers pivoted intermediate their ends upon laterally projecting lugs 68 and 69 respectively of the heads 2 and 3, and 70 and 71 respectively are rollers carried by the levers 66 and 67 at the upper 100

ends thereof and engaging the side walls of the grooves 64 and 65 respectively in the collars 62 and 63.

- In the present instance the castings to be drilled are fed onto and travel longitudinally of downwardly and inwardly inclined chutes 72 and 73 respectively into engagement with substantially L-shaped stops 74 and 75 respectively from which they are removed laterally by means of drills 76 and 77 respectively into the collets 20 and 21. As shown, the chutes 72 and 73 are bolted to brackets 78 and 79 slidably mounted upon the raised portions 9 of the frame top 6. Preferably spacers 80 and 81 respectively are used between the raised portions 9 of the frame and the bases of the brackets 78 and 79 so that the lower ends of the latter will be at the proper elevation with respect to the drills 76 and 77. Any suitable means such as the bolts 82 having inverted T-shaped heads 83 slidably engaging correspondingly shaped grooves 84 in the raised portions 9 of the frame top 6 may be employed for adjustably connecting the chute brackets 78 and 79 respectively to the frame. The stops 74 and 75 have depending portions 86 and 87 respectively bolted to the brackets 78 and 79, while the drills 76 and 77 are arranged in stepped relation upon a carriage 88 slidably mounted upon a raised portion 89 of the top 6 of the frame. Preferably the drills 76 and 77 are clamped by plates 90 and 91 against a plate 92 bolted to the carriage 88.
- 93 is a rack bolted to the under face of the carriage 88; and 94 is a gear sector mounted upon a stub shaft 95 journaled in a bearing 96 secured to the frame 1 at one side thereof. 97 is a lever rigid with the gear sector 94 and extending downwardly therefrom beneath the stub shaft 95; 98 is a lever secured at its lower end to a stub shaft 99 journaled in a bearing 100 secured to the frame 1 at one side thereof; and 101 and 102 respectively are link sections connected together by shearable pins 103 and 104 respectively and having end portions 105 and 106 respectively terminally connected to the levers 97 and 98 respectively adjacent the free ends thereof. Preferably the end portions 105 and 106 are slidable longitudinally in slots 107 and 108 respectively in the levers 97 and 98 so that adjustments may be made as desired to vary the sliding movement of the carriage 88 so that the position of the drills 76 and 77 carried by said carriage may be varied with respect to the collets 20 and 21 respectively in the heads.
- 109 is a cam shaft journaled in bearings 110 and 111 respectively upon the frame; 112, 113 and 114 are cams upon the cam shaft 109 and having cam grooves 115, 116 and 117 respectively therein; 118, 119 and 120 respectively are cam rollers engaging the

grooves 115, 116 and 117; 121 and 122 respectively are pins projecting from the rollers 118 and 119; 124 is a sectional link terminally connected to the pin 121 and to the lever 66; 125 is a sectional link terminally connected to the pin 122 and to the lever 67; and 126 is a pin projecting from the cam roller 120 and secured to the lever 98 adjacent the free end thereof. 127 is a drive shaft journaled in bearings 128 and 129 upon the frame; 130 is a stub shaft journaled in the bearing 129; 131 and 132 are gears rigid with the shafts 127 and 130 respectively and meshing with each other; 133 is a pinion on the stub shaft 130; 134 is a gear keyed upon the cam shaft 109 and adapted to be rotated by the pinion 133; 135 is a shiftable clutch collar of suitable design controlling the driving connection between the stub shaft 130 and pinion 133; 136 is a shifter fork for the collar 135; 137 is a rock shaft rigid with the shifter fork 136 and extending transversely of the frame 1 of the machine; and 138 is an operating lever rigid with the outer free end of the rock shaft 137. 139 is a stub shaft journaled in the bearing 110; 140 is a pulley rigid with the stub shaft 139 and adapted to be driven from a suitable source (not shown) by a belt 141; 142 is a pinion rigid with the stub shaft 139 at the inner end thereof; and 143 is a gear rigid with the shaft 127 and meshing with the pinion 142.

In use, castings such as 144 constituting the work, are supplied to the chutes 72 and 73 so that they may roll down the chutes for successive engagement with the stops 74 and 75 respectively. When the clutch collar 133 is actuated by the lever 138 to establish a driving connection between the stub shaft 130 and the pinion 133 in mesh with the cam shaft gear 134, the cam 114 will actuate the lever 98 and will cause the gear sector 94 to reciprocate the carriage 88 relative to the collets 20 and 21 so that the drills 76 and 77 respectively will alternately remove castings from the stops 74 and 75 respectively into the collets 20 and 21 respectively. Rotation of the cam shaft 109 also causes the cams 112 and 113 to reciprocate the links 124 and 125 respectively so that the levers 66 and 67 will shift the collars 62 and 63 respectively into and out of engagement with the dogs 56. In this connection it will be noted that the cam grooves 115 and 116 respectively in the cams 112 and 113 are oppositely arranged so that when one collar such as 62 is in engagement with the dogs 56 in the collar 52, the other collar 63 is disengaged from the dogs 56 in the collar 53. Inasmuch as the dogs 56 cause the rams 34 and 35 respectively to move the collets 20 and 21 respectively inwardly against the conical faces 18 and 19 of the caps 16 and 17 so that the gripping sur-

faces 26 and 27 of said collets grip the casting 144 inserted into the collets by the respective drills 76 and 77, it will be apparent that when the dogs 56 are engaged by the collar 62 the casting 144 inserted into the collet 20 by the drill 76 will be gripped by the surface 26 of the collet so that the casting will be held securely while the drill 76 is advanced further by the action of the cam 114 to effect the drilling operation. Upon completion of this drilling operation the cam 114 will cause the carriage 88 to move in the opposite direction so that the drill 76 will be removed from the casting 144 in the collet 20 and will cause the drill 77 to remove a new casting from the stop 75 and to insert the said casting into the collet 21 so that it may be gripped by the gripping surface 27 of said collet. During this operation the lever 66 is moved by the cam 112 so that the collar 62 is disengaged from the dogs 56 in the collar 52, and the lever 67 is moved by the cam 113 so that the collar 63 is engaged with the dogs 56 in the holder 53. As a result the casting 144 in the collet 20 will be released by the gripping surfaces 26 and the new casting received in the collet 21 will be securely held by the gripping surfaces 27 of the collet 21. Rotation of the cam 114 then causes the drill 77 to be advanced further to effect the drilling operation of the casting 144 in the collet 21. Continued operation of the machine causes the carriage 88 to be again moved to the left so that the drill 76 will remove a new casting from the stop 74 and will insert it into the collet 20. In doing so, the new casting abuts the drilled casting 144 in the collet 20 and causes the said drilled casting to be moved longitudinally of the collet toward the discharge opening 145 at the outer end of the reduced portion 46 of the ram. Likewise continued operation of the machine causes the carriage 88 to again be moved to the right so that the drill 77 will remove a new casting from the stop 75 and insert it into the collet 21 so that it may be gripped by the gripping surface 27 of the collet 21. In doing this the new casting will abut the drilled casting and will cause it to be moved longitudinally of the collet toward the discharge opening 146 at the outer end of the reduced portion 47 of the ram 35. Any suitable means (not shown) may be employed for receiving the drilled castings after they fall from the discharge openings 145 and 146 respectively aforesaid.

Thus from the foregoing description it will be apparent that when one drill is withdrawn from the work the other drill is moved into engagement with the work and vice versa, and that the drilled castings constituting bushings are successively advanced longitudinally of the spindles from the re-

spective collets to the discharge openings 145 and 146 respectively. In other words, no discharging time is lost. When a new casting is inserted into a collet it automatically causes a drilled casting to be discharged from the machine.

Any chips formed as a result of the drilling operations are free to work through the slots 24 and 25 respectively in the collets 20 and 21 and will be removed by centrifugal force outwardly through holes 20' and 21' in the caps 16 and 17. Moreover, the provision of the conical surfaces 40, 41, 42 and 43 respectively at the forward ends of the sleeves 28 and 29 and rams 34 and 35 preclude such chips from binding at these points and have a tendency to deflect the chips so that they may be discharged through the slots 24 and 25 and openings 20' and 21' respectively. It will also be apparent that the movements or strokes of the carriage 88 may be regulated by the adjustment of the end portions 105 and 106 respectively of the link sections 101 and 102 longitudinally of the levers 97 and 98, and that the heads 2 and 3 may be adjusted toward and away from each other when the bolts 8 are released.

In Figures 4 to 6 inclusive I have illustrated a slight modification in which cutter bars 200 and 201 respectively having cutters 202 and 203 respectively projecting from diametrically opposite sides of said bars are utilized instead of the drills 76 and 77 for forming longitudinally extending oil grooves in tubular castings 144'. As shown, these cutter bars 200 and 201 are held by plates 204 and 205 bolted to the plate 206 carried by the slide 88. An auxiliary slide 207 is carried by the plate 88 and is alternately engageable with the caps 16 and 17 respectively upon reciprocation of the slide 88. Preferably, the slide 207 is held stationary by friction in the main slide 88 while moving between the caps 16 and 17 and is arranged in line with the stops 74 and 75 so that opposite ends 208 and 209 respectively of the auxiliary slide may be utilized as rams for alternately removing new castings from said stops and inserting them into the collets 20 and 21 to be gripped by the surfaces 26 and 27 respectively thereof. In this construction the pulleys 12 and 13 have been dispensed with entirely, and the spindles 10 and 11 in this instance carry gears 210 and 211 respectively which are engaged by gear sectors 212 and 213 mounted upon stub shafts 214 and 215 journaled in bearings 216 and 217 upon the cover plates 218 and 219 upon the heads 2 and 3 respectively. Preferably L-shaped plates 220 and 221 are bolted to the carriage 88 at opposite ends thereof, and cams 222 and 223 respectively are carried by the upright portions of said plates 220 and 221 and have inclined cam

grooves 224 and 225 respectively therein that receive rounded end portions 226 and 227 respectively of the gear sectors 212 and 213. Thus with this construction when the slide 88 is reciprocated the cams 222 and 223 carried thereby will cause the gear sectors 212 and 213 to rock upon their pivots 214 and 215 and rotate the gears 210 and 211 rigid with the spindles 10 and 11 so that the castings 144' will be given a quarter turn as the cutters 202 and 203 are advanced longitudinally of said castings. As a result the cutters 202 and 203 form longitudinally extending spiral grooves in the castings 144'.
 15 In use, when the carriage 88 is moved to the left by the gear sector 94 actuated by the cam 114 the auxiliary slide 207 will be held by friction in the main slide 88 and will remove a new casting from the stop 74 and will insert it into the collet 20. Upon abutting the cap 16 the auxiliary slide 207 will remain stationary and continued movement of the main slide 88 relative thereto causes the cutter bar 200 to be advanced into and 20 longitudinally of the casting 144'. As the main slide 88 moves to the left the plate 220 will also move therewith so that the cam 222 will cause the sector 212 to rotate the spindle 10 so that the bushing 144 will be correspondingly rotated. As a result, the cutters 202 upon diametrically opposite sides of the cutter bar 200 will form a longitudinally extending spiral groove in the casting 144' as it is advanced longitudinally thereof.
 30 The main slide 88 will then be moved by the gear sector 94 to the right and in doing so will cause the auxiliary slide 207 to move therewith, and will cause the cutter bar 200 to be withdrawn from the grooved casting 144'.
 35 The auxiliary slide 207 will be held by friction in the main slide 88 and will remove a new casting from the stop 75 and will insert it into the collet 21. Upon engagement of the end 209 of the auxiliary slide 207 with the cap 17, the auxiliary slide 207 will remain stationary while the main slide 88 will continue its movement to the right and will cause the cutter bar 201 to be advanced into and longitudinally of the new 40 casting 144' in the collet 21 so that the longitudinally extending spiral groove may be formed therein upon rotation of the spindle 11 by the gear sector 213 in the manner previously described. In this construction, 45 as in the construction illustrated in Figures 1 to 3 inclusive the grooved castings 144 are advanced longitudinally of the collets to the discharge openings 145 and 146 respectively as the new castings are inserted into the 50 respective collets by the auxiliary slide 207. Thus the modified construction has the same advantages from an efficiency standpoint as the construction illustrated in Figures 1 to 3 inclusive.
 55 While it is believed that from the foregoing

ing description the nature and advantages of the invention will be readily apparent, I desire to have it understood that I do not limit myself to what is herein shown and described and that such changes may be resorted to when desired as fall within the scope of what is claimed.

What I claim as my invention is:

1. In a machine of the class described, a head, a spindle mounted to turn in said head, a cap carried by the spindle, work gripping means including a collet movable longitudinally of the spindle and operable upon engagement with the cap to grip the work, and actuating means for the collet including a work receiving member movable in the head as a follower for the collet, said longitudinally movable member having inclined means for deflecting toward said collet chips and other particles removed from the work while gripped by said collet, and said collet and cap having registering openings permitting said chips and other particles to be discharged laterally outwardly therefrom.

2. In a machine of the class described, a pair of spaced heads, work gripping means carried by said heads, work chutes adjacent said heads, a carriage movable between said heads, and tools non-rotatably carried by said carriage for removing work from said chutes and moving it into engagement with the gripping means in said heads.

3. In a machine of the class described, a pair of spaced heads, means in said heads for gripping the work, a carriage movable between said heads, work engaging tools carried by said carriage and alternately engageable with work held by said gripping means, and actuating means for the carriage including a rack carried by the carriage, a gear sector engaging the rack, a cam spaced from the gear sector, and an adjustable driving connection between said cam and gear sector.

4. In a machine of the class described, a pair of spaced heads, work-gripping means carried by said heads, a reciprocating carriage, between said heads, tools projecting from opposite ends of said carriage for engagement with work in said gripping means, a rotary cam, and a driving connection between the cam and carriage adjustable to vary the movements of the carriage and tools relative to the heads and work-gripping means including a rack rigid with the carriage, a gear sector engaging the rack, a lever rigid with the sector, a lever adjacent the lever just mentioned and operatively connected to the cam, and a slideable connection between said levers.

In testimony whereof I affix my signature.
 GEORGE F. YAGER.
